UNITED STATES PATENT OFFICE.

CHARLES W. NICHOLAS, OF TARENTUM, PENNSYLVANIA, ASSIGNOR TO WALTER P. MURPHY, OF CHICAGO, ILLINOIS.

COUPLING-RELEASE RIGGING.

1,322,934.

Specification of Letters Patent.

Patented Nov. 25, 1919.

Application filed August 23, 1917. Serial No. 187,785.

To all whom it may concern:

Be it known that I, CHARLES W. NICHOLAS, a citizen of the United States of America, residing at Tarentum, in the county of 5 Allegheny and State of Pennsylvania, have invented certain new useful Improvements in Coupling-Release Rigging, of which the following is a specification.

My invention resides in certain improvements in the construction of release rigging 10 for car couplers shown in the patent to Deissler & Dickinson No. 1,198,012 dated September 12, 1916, and resides more particularly in improved means for securing the 15 pin lifting link to the crank of the operating rod.

Most of the railroads have cars equipped 20 with what is known as the chain lifting release mechanism, wherein a rod is revolubly mounted in closed brackets on the end of a car, said rod having a crank at its inner end which extends outwardly from the end of the car, the outer end of said crank usually having an eye disposed at right angles to the 25 draw bar, the lock pin of the coupler being connected to the outer end of the crank by means of a chain having clevises, pins and cotters.

This chain connection between the lever 30 and lock pin is objectionable because of the fact that the links of the chain frequently become entangled whereby a defective operation of the releasing mechanism is brought about. The objection to the chain connection has been solved in many ways but in the 35 solution of this problem the entire release rigging mechanism was reconstructed and it became necessary for the railroads to discard the old rod which was mounted on the 40 car and the discarding of these old rods resulted in a very material loss and expense to the railroads.

In the patent above referred to is shown 45 the first practical solution of a substitution for the chain, of a rigid connection between the lock pin and the crank of the old operating rod but in the construction of said patented device it has been found that the use of a bolt with a cotter pin subjects the device 50 vice to some defects, that is to say the parts are apt to become loose and lost whereupon the device would become inoperative.

If the rigid link shown is applied to the 55 operating rod in a shop it would necessitate the use of open brackets on the end of the car

or the removal of the closed brackets from the car, therefore one of the objects of my invention is to apply the pin lifting link to the crank of the operating rod securely and against accidental displacement, and thus 60 eliminate the necessity of purchasing open brackets, or the expense of removing closed brackets from the car.

The principal object of my invention is to 65 secure a rigid pin lifting link, of the general character illustrated, to an operating rod while it is mounted in closed brackets on the car, in such a manner that the link is securely attached to the operating rod against 70 accidental displacement.

Another object of my invention is to provide means whereby the rigid pin lifting link is firmly secured against accidental displacement to the operating rod, while said rod is secured on the car, and at the same 75 time leave the pin lifting link free to slide relatively to the operating rod.

A further object of my invention is to rivet the rigid pin lifting lever to the crank of an operating rod in such a manner that 80 the link is free to slide relatively to the operating rod.

A further object of my invention is to secure the pin lifting link against accidental displacement to the operating rod by means 85 of a rivet and provide means on said rivet whereby the under face of the upset rivet head is spaced from the face of the link, whereby the link is free to move relatively to the operating rod; a further object of my invention is to provide a pin lifting link 90 having an elongated vertically disposed slot in its upper end, and secure the link to the operating rod by passing a rivet through an eye in the operating rod and through 95 said slot and providing the rivet with an abutment, spaced from the plane of the outer face of the link against which abutment the end of the rivet is upset, whereby the inner face of the upset head of the rivet is spaced from the upper end of the 100 link, so that the link is free to move relatively to the operating rod; and with these and other objects in view my invention consists of the parts and combination of parts as will be hereinafter set forth.

In the drawing:—

Figure 1 is a side elevation of a coupler release rigging embodying my invention.

Fig. 2 is a front elevation of the same.

Fig. 3 is an enlarged side elevation of the link attached to the operating rod.

Fig. 4 is an enlarged front elevation of the link, the operating rod being shown in section.

Fig. 5 is a side elevation of the rivet.

The reference numeral 1 designates a coupler of standard design provided with a lock pin 2 which has an opening 3 extending transversely of the coupler bar.

The pin lifting link 4 is provided at its lower end with suitable hook 5, which may be of the type shown in the patent to Gilpin 1,181,952 or any approved design. The upper portion of the link 4 is formed of two side members 5^a and 6 connected at the top by the spacing member 7 whereby a housing is formed to receive the outer end portion of the operating rod 8 as clearly shown in Fig. 4. The said members 5^a and 6 are each provided with an elongated slot 9 extending lengthwise of the link as clearly shown in Fig. 3.

A rivet 10 having a head 11 is passed through the eye in the inner end of the operating rod and through the elongated slots 9 of the pin lifting link and said rivet is provided at its other end with a reduced portion 12, and a shoulder or abutment 13, which shoulder or abutment is at the junction of the reduced portion 12 and the main body of the rivet 10; when the parts are assembled this shoulder 13 is spaced beyond the vertical plane of the said member 6 and a washer or other abutment 14 is positioned on the reduced portion 12 and abuts against the shoulder 13 thereby constituting an abutment which is spaced from the outer face of the said member 6 of the link, against which the reduced portion 12 may be upset to form a head for the rivet. The abutment acts as a spacing member whereby the under face of the upset or riveted head is spaced from the outer face of the link 4, whereby the link is free to move relatively to the operating rod 8, notwithstanding the parts are riveted together. By reason of the washer 14, shoulder 13 and reduced portion 12, I am enabled to obtain a comparatively small rivet head which can be easily driven cold by manual labor and thereby dispense with power hammers, whereby the lifting link may be readily attached against accidental displacement to the operating

rod, while the operating rod is secured to 55 the car.

It will be readily seen that by reason of the construction shown and described there is no danger of the said members 5 and 6, and the housing constituted therby being 60 collapsed or pressed toward each other and binding the link to the operating rod against relative movement.

It will also be seen that by reason of the construction shown and described it is not 65 necessary to make the eye in the inner end of the operating rod, and the slots of the link, of materially larger diameter than the diameter of the body of the rivet, whereby I am enabled to use a rivet of maximum 70 diameter.

It will also be seen that by reason of the construction shown and described that the link can be attached to the operating rod without special tools and that all of the 75 parts are secured against accidental displacement, whereby the loss of parts, and likelihood of damage due to the loss of parts, is eliminated.

What I claim is:--

A lock pin lifting link adapted to have an uncoupling lever and lock pin of a coupler connected therewith and including a housing the side walls of which are spaced from the lever and have elongated slots, a 85 rivet of a length greater than the outside transverse dimension of the housing, terminating at one end in a reduced portion, a shoulder at right angles to the axes of the reduced portion, the distance between the 90 shoulder and the under face of the head of the rivet being greater than the outside dimension of the housing hood, a washer on the reduced portion, whereby the rivet may be passed through the housing and its other 95 end upset against the washer without distorting the housing, whereby the link is free to move bodily vertically relatively to the rivet and whereby the lower end of the 100 link is free to move to accommodate the service movements of the coupler without imposing strains upon the parts.

In the testimony whereof I affix my signature in the presence of a witness.

CHARLES W. NICHOLAS.
